ELECTRICAL PRECIPITATOR

Hans Klemperer, Belmont, Mass., assignor to
 Raytheon Manufacturing Company, Newton,
 Mass., a corporation of Delaware

Application October 16, 1946, Serial No. 703,504

2 Claims. (Cl. 183—7)

1

This invention relates to electrical precipitators for separating dust, smoke, and similar impurities from air or other gases. More particularly, the invention relates to a precipitator of the type in which an alternating potential is applied to the electrodes of the precipitator.

In my copending application Serial No. 678,155, filed June 20, 1946, now Patent No. 2,542,035, dated February 20, 1951, there is disclosed a precipitator in which the ionizing device thereof is supplied with an alternating current without the necessity of providing rectifiers between the source and the ionizing electrodes. The present invention concerns a construction in which both the ionization of the air or other gases and the precipitation and collection of dust particles are effected by means of alternating potential without the necessity of providing rectifiers for either the ionization or collection of the dust particles.

To these ends the invention contemplates construction in which an alternating potential is applied to a plurality of electrodes of the type adapted to effect both ionization and collection, the number and length of said electrodes being correlated to the number of phases of the power supply, the frequency of said power supply and the velocity of air or other gas passing the electrodes.

Accordingly, it is among the objects of the invention to provide a precipitator in which the necessity of providing rectifiers for effecting either ionization or collection is avoided.

The above and other objects and features of the invention will be made fully apparent to those skilled in the art from a consideration of the following detailed description taken in conjunction with the accompanying drawing in which:

Fig. 1 is a diagrammatic view of an electrical precipitator which illustrates the principles of the invention;

Fig. 2 is a schematic illustration representing gas conditions in my device at the ends of successive time intervals;

Fig. 3 is a series of voltage waveforms useful in explaining the operation of the invention; and

Fig. 4 is a view similar to Fig. 1 showing an apparatus constructed in accordance with the invention.

Referring to the drawing, and first to Fig. 1, reference numeral 10 indicates generally a three-phase transformer having Δ -connected primary windings 12 and Y-connected secondary windings 14. The outer terminals 16, 18 and 20 of the Y secondary windings of the transformer 10 are

directly connected, respectively, to the ionizing electrodes 17, 19 and 21. The neutral point 23 of the secondary windings is directly connected to a metallic casing 22 providing an air channel surrounding the electrodes 17, 19, and 21. Preferably the connection between the center point 23 and the channel 22 is grounded. The wire electrodes 17, 19 and 21 are arranged in alignment, each extending longitudinally of the channel 22, and are so spaced with respect to the direction of air flow and the speed of the air passing through the channel 22 that portions of the air to be cleaned are acted upon successively by each of the electrodes 17, 19 and 21 to the end that during the positive peaks of potential upon any one of the electrodes 17, 19 and 21 the air passing the electrode at which a positive peak occurs will be ionized and the dust particles precipitated upon walls of the channel 22 forming a common grounded electrode. The length of each of the electrodes 17, 19 and 21 is so correlated to the velocity of the air passing through the channel 22 that, during the positive peak upon a given wire electrode, the air in channel 22 will traverse a distance equal to the length of the electrode. It will be understood that the duration of the positive peak upon any given electrode does not correspond to the full half-wave of positive potential upon the electrode. The potential must reach a value of some 6 kv. before an ionizing discharge can occur. Accordingly during the early portion of the positive half-wave upon a given electrode the potential is insufficient to produce an ionizing discharge. Similarly, as the potential drops from the positive peak toward the end of the positive half-wave of potential upon the electrode, the potential is again insufficient to effect an ionizing discharge. However, during this latter portion of the positive half-wave, the potential will, nevertheless, aid in the movement of the charged dust particles to the collecting electrode.

Accordingly, during approximately 120° of the positive half-wave of potential upon any given electrode, the potential will be sufficient to effect both ionization and collection of the dust particles.

The length of each of the ionizing electrodes 17, 19 and 21 is so correlated to the velocity of the air through the channel 22 that the time interval of approximately 120° of the positive half-wave upon any electrode will allow the air originally at the upstream end of this electrode to just reach the opposite end of the electrode at the end of such positive peak. Thus, if the length

of the wires is such that when the positive peak of one phase is effective in zone A, the body of air traversing this zone will be ionized and the dust particles thereof collected during this positive peak.

The air in the zones B and C will be untreated. The condition of the air at the end of this first positive peak effective in the zone A is shown in column I of Fig. 2 in which the stippling indicates ionized air and dust particles in the process of collection. If the positive peak of the next successive phase is effective upon the electrode 21, the untreated air in the zone B at the beginning of this positive peak will be ionized and the dust particles collected as it is displaced from the zone B into the zone C. The body of the treated air in the zone A at the beginning of the second positive peak will have moved into the zone B by the end of this second positive peak effective on the electrode 21. The state of the air in the various zones at the end of the second positive peak of potential is indicated in column II of Fig. 2.

It is seen that the untreated air present in the zone B at the end of the first positive peak has, by the end of the second positive peak, been displaced into the zone C where it has been ionized and the dust particles precipitated. In the meantime the ionized air originally in the zone A at the beginning of the second positive peak has been displaced into the zone B. The positive peak of the third phase is effective upon the electrode 19. The untreated air in the zone A at the beginning of this third phase is displaced into the zone B during the positive peak of this phase, and is ionized and dust particles precipitated. The state of the air in the various zones at the end of the third positive peak of potential is indicated in column III of Fig. 2. It will thus be seen that during the three successive phases of any three-phase cycle all portions of the air passing through the channel 22 are acted upon, particular portions thereof being acted upon by each of the electrodes in turn and all portions thereof being acted upon by at least one of the electrodes. Thus no portion of the air passing through the channel 22 escapes treatment.

The cycle thereupon repeats itself, the first phase of the second cycle being again effective upon the electrode 17. The state of the air in the various zones at the end of this first phase of the second cycle will be as indicated in column IV of Fig. 2. The second phase of the second cycle is again effective upon the electrode 21 and the state of the air in the various zones at the end of this second positive peak of potential of the second cycle is shown in column V of Fig. 2. The third phase of the second cycle is again effective upon the electrode 19, and the state of the air in the various zones at the end of the third positive peak of potential of the second cycle is indicated in column VI of Fig. 2.

It will be understood that a negative potential is also applied to each of the electrodes 17, 19 and 21 during each cycle of the three phases of potential; however, this negative potential is less effective in the ionization of the air than the positive peaks of potential. The present invention insures that each portion of the air to be treated will be subjected to the highly ionizing effect of a positive peak of potential upon one of the electrodes and the less effective ionization of the negative peaks of potential is additive to the effective ionization and collection to which

each portion of the air is subjected during one positive peak of potential of the three-phase cycle.

As shown in Fig. 3, the positive peaks of potential of a sine wave may rise considerably above the potential necessary to effect an ionizing discharge. In order to smooth out the positive peaks, resistors 25, 26 and 27 may be inserted in each of the conductors between the terminals 16, 18 and 20 and the electrodes 17, 19 and 21, respectively. These peak current-limiting resistors thus provide wave forms of the type indicated by solid lines in Fig. 3, rather than the wave form indicated by dotted lines which occurs where these resistors are omitted. Accordingly, during that portion of the positive half-wave on any given electrode in which the potential is rising to or falling below the value at which an ionizing discharge occurs, the resistor in the electrode circuit concerned has no material effect upon the wave form. During the portion of the positive half-wave in which the potential is above the value at which an ionizing discharge occurs, the resistor offers an impedance to the flow of current and thus prevents the voltage on the electrode from rising to the peak value that would otherwise occur. The portion of the positive half-wave during which the potential is rising to the value at which an ionizing discharge occurs covers about 30° of the total 180°. During the following 120° the potential will be above the ionizing potential and during the final 30° the potential will again be below the ionizing potential.

Referring now to Fig. 4, the present invention is illustrated. In this figure, reference numeral 30 indicates a transformer having a primary winding 31 connected across the terminals of an alternating current source. The secondary winding 32 of the transformer 30 has one end connected through a resistance 33 to a fine wire electrode 34. The other terminal of the secondary winding 32 is connected through a resistor 35 to a fine wire electrode 36. The electrodes 34 and 36 are, as in the construction previously described, disposed longitudinally of a tubular member 37 providing an air channel, which channel is of metallic material and grounded, as indicated at 38. In this instance, the electrodes 34 and 36 are spaced by distances substantially equal to their length, providing a zone B' therebetween in which no ionization occurs. The length of the electrodes 34 and 36 is so correlated to the velocity of air flow that, during the positive peaks of potential upon either of the electrodes, the air flowing through the channel traverses the length of the electrode. Thus, when the potential is positive upon the electrode 34, the air in zone A' is ionized and dust particles precipitated and a body of untreated air will be present in the zone B' between the electrodes 34 and 36. On the next half-wave of the single phase source the potential on the electrode 36 will be positive and the untreated air in the zone B' will be ionized and dust particles precipitated as it moves into and through the zone C'. In the meantime the air previously treated in the zone A' will move into the zone B' so that, at the end of the positive half-wave of potential upon the electrode 36, the bodies of air treated in the zones A' and C' constitute a continuous stream of treated air with no intervening portions of untreated air therebetween. The cycle thereupon repeats itself.

While there have been herein described a preferred embodiment of the invention, other embodiments within the scope of the appended claims

will be apparent to those skilled in the art from a consideration of the forms shown and the teachings hereof.

What is claimed is:

1. An electrical precipitator comprising means defining an elongated passage for a gas stream, said passage comprising first, second and third sequentially disposed zones of substantially equal extent, an ionizing electrode in each of said first and third zones only, said electrodes each being elongated and of substantially the same length as the zone it occupies, said electrodes being further disposed endwise in said tube with said second zone between their confronting ends, a source of alternating potential connected at one side to one of said electrodes and at the other side to the other electrode, means to pass gas to be cleaned in a continuous stream through said passage and successively past each of said first, second and third zones at a prescribed velocity, said velocity being chosen to provide that during a first half cycle of the alternating potential the gas in said first zone is ionized and in the succeeding half cycle the gas that was in said second zone during the first half cycle arrives in said third zone and is ionized.

2. An electrical precipitator comprising means defining an elongated passage for a gas stream, said means being an electrically conductive tube surrounding the passage and being electrically grounded, said passage comprising first, second and third sequentially disposed zones of substantially equal extent, an ionizing electrode in

each of said first and third zones only, said electrodes each being elongated and of substantially the same length as the zone it occupies and insulated from said tube, said electrodes being disposed endwise in said tube with said second zone between their confronting ends, a source of alternating potential connected at one side to one of said electrodes and at the other side to the other electrode, means to pass gas to be cleaned in a continuous stream through said passage and successively past each of said first, second and third zones at a prescribed velocity, said velocity being chosen to provide that during a half cycle of the alternating potential the gas in said first zone is ionized and in the succeeding half cycle the gas that was in said second zone during the first half cycle arrives in said third zone and is ionized.
